(57) **CLAIM**

The ornamental design for a water tray, as shown and described.

DESCRIPTION

FIG. 1 is a perspective view of the front, top, and right side of the water tray;

FIG. 2 is a perspective view of the front, bottom, and left side of the water tray;

FIG. 3 is a front view of the water tray;

FIG. 4 is a rear view of the water tray;

FIG. 5 is a left side view of the water tray;

FIG. 6 is a right side view of the water tray;

FIG. 7 is a top view of the water tray; and,

FIG. 8 is a bottom view of the water tray.

The broken lines in FIGS. 1-8 show portions of the water tray that form no part of the claimed design.

1 Claim, 7 Drawing Sheets
